UNITED STATES PATENT OFFICE.

RICHARD D. GALLAGHER, JR., OF NEW YORK, N. Y., ASSIGNOR TO
STANDARD COUPLER COMPANY, OF SAME PLACE.

DRAFT OR BUFFING RIGGING.

SPECIFICATION forming part of Letters Patent No. 681,210, dated August 27, 1901.

Original application filed April 8, 1901, Serial No. 54,900. Divided and this application filed July 1, 1901. Serial No. 66,727.
(No model.)

To all whom it may concern:

Be it known that I, RICHARD D. GALLAGHER, Jr., a citizen of the United States, residing at New York, in the county of New York and State of New York, have invented certain new and useful Improvements in Draft or Buffing Rigging; and I do hereby declare the following to be a full, clear, and exact description of the same, reference being had to the accompanying drawings, forming a part of this specification, and to the figures of reference marked thereon.

This invention relates to improvements in rigging designed to yield and take up strains of parts moved by heavy pressure; and while the invention is well adapted for use in connection with heavy mechanism or mechanism operating under heavy pressure, such as ordnance, wherein the recoil must be checked, it is particularly designed to answer the requirements of the draft-rigging for cars, and more especially rigging of heavy rolling-stock—as, for instance, the modern steel cars of large capacity.

In its application to draft-rigging for cars the invention is designed to be capable of ready application to cars of practically any type and having either steel or wood draft-timbers or framing.

To this end one of the objects of the invention is to provide a structure capable of being readily substituted for draft-rigging on rolling-stock now in use or applied to rolling-stock in course of construction without cutting to any material extent the draft-timbers when of wood or modifying the framing when of metal.

A further object of the invention is to provide a structure in which the springs may be arranged in the line of pressure and at the same time their resistance so augmented and modified that springs of ordinary standard size and power may, where desired, be utilized for the draft-rigging of rolling-stock of practically unlimited weight and without occasioning shock or oscillation of the cars in starting, stopping, or varying speed and regardless of the length of the train.

The present application is a division of my

prior application, Serial No. 54,900, filed April 8, 1901, and is designed to cover that form of mechanism wherein the movement of the pressure-transmitting member in either direction is converted into a reverse movement in compressing the spring, and whereby the structure may be adapted to compress the spring by opposite movements of its confining-abutments, the resistance of the spring being augmented by the resistance due to the friction and wedging action of the members intermediate the spring and pressure-transmitting member.

Referring to the accompanying drawings, Figure 1 is a vertical section through a draft-rigging embodying the present improvements. Fig. 2 is a top plan view of the same.

Like numerals of reference in both figures indicate the same parts.

In the application of the invention to a draft-rigging of railway-cars the working parts of the mechanism are preferably sustained between cheek-plates, which may be of suitable design to adapt them for attachment to the sills or draft-timbers of the car-frame, and in the preferred type these cheek-plates are made as nearly as possible to conform to the requirements of car-frames of any construction now in use or so as to be capable of application thereto without modification, but simply by varying the mode of attachment. In the present instance, as in the usual forms of draft-rigging, the working parts of the apparatus are supported and work between suitable supports—such, for instance, as the cheek-plates 1, having suitable stops and guides 2 for the followers. The cheek-plates are simply a type of supporting mechanism, and it is obvious that any other or preferred type may be substituted. The spring 3 is mounted between followers 4, the latter being carried by the cheek-plates and held by the stops 2 against outward movement, but are free to move inwardly or toward each other and back to normal position.

Surrounding the followers and spring is a frame 5, corresponding to the ordinary strap, only preferably heavier and stronger than

the usual strap, said frame being attached at one end to the draw-bar 6. The frame 5 constitutes part of the pressure-transmitting member, and between it and the followers a mechanism is provided which will convert the movement of the frame in one direction to a reverse movement of the forward follower, thereby compressing the spring reversely and augmenting its resistance by the frictional and wedging resistance of the motion-converting mechanism.

The mechanism referred to consists of a transversely-movable wedge-block adapted to be displaced transversely by the frame and to itself displace the follower in the opposite direction to the movement of the frame. The wedge-block (indicated by the numeral 7) is adapted to be displaced transversely by incline 8 on the frame 5 and in turn co-operates with the incline 9 on the follower 4, whereby the follower is displaced linearly and in direction opposite to the direction of movement of the frame. The wedge-block is guided in its transverse movement by a cross or follower plate 10, held by the supports or cheek-plates.

The mechanism is preferably duplicated at each end of the spring, the parts being reversely arranged, and in order that the device may be double-acting in both directions, so as to compress the spring from both ends, the cross or follower plates are mounted between stops 11, so as to be capable of an inward movement, whereby on movement of the pressure-transmitting member the rear cross or follower plate will advance and carry with it as a body the wedge-block and follower, while the other cross or follower plate will remain stationary, and the incline on the frame, acting through the wedge-block and follower-incline, will move the forward follower backwardly against the tension of the spring.

The mechanism operates in like manner in either direction, and it is obvious that by changing the angle of the inclines the resistance, due to friction and wedging action of the parts, may be varied to suit the conditions under which the apparatus is designed to work, and thus standard springs may be employed for all classes of work, and while with the structure shown the spring is adapted to be compressed from both ends it is obvious that the wedging devices alone may be utilized for each movement, thereby compressing the spring from one end only.

Having thus described my invention, what I claim as new, and desire to secure by Letters Patent, is—

1. In an apparatus of the character specified, the combination of the following instrumentalities, to wit; a pressure-transmitting member, an incline moving therewith, a wedge-block adapted to be displaced transversely by said incline, a follower co-operating with the wedge-block and adapted to be displaced thereby in a direction opposite to the direction of movement of the pressure-transmit-

ting member and a spring for resisting the movement of the follower, as set forth.

2. In an apparatus of the character specified, the combination of the following instrumentalities, to wit; a spring, a follower working against said spring, an incline moving with said follower, a transversely-movable wedge-block co-operating with the incline to displace the follower against the tension of the spring, a transverse guide for the wedge-block, a pressure-transmitting member movable in line with the line of spring-compression and an incline moved by the pressure-transmitting member and co-operating with the wedge-block to displace the same transversely; substantially as described.

3. In an apparatus of the character specified, the combination with followers, stops for holding said followers against outward movement while permitting them to move inwardly, and a spring confined between said followers, of an incline moving with one of said followers, a transversely-displaceable wedge-block co-operating with said incline, a pressure-transmitting member and an incline moving therewith and co-operating with the wedge-block to displace the same transversely against the tension of the spring exerted through the follower and incline moving therewith; substantially as described.

4. In a draft-rigging the combination with the followers having inclines on their outer sides, a spring confined between the followers and transversely-movable wedge-blocks co-operating with said inclines, of a pressure-transmitting member, inclines moving therewith and co-operating with the wedge-blocks, and guides with which the wedge-blocks co-operate in their transverse movement; substantially as described.

5. In a draft-rigging, the combination with the followers having inclines on their outer sides, a spring confined between the followers, and transversely-movable wedge-blocks co-operating with said inclines, of a pressure-transmitting member, inclines moving therewith and co-operating with the wedge-blocks and guides formed by inwardly-movable cross-plates with which the wedge-blocks co-operate in their transverse movement; substantially as described.

6. In a draft-rigging, the combination with the spring, the longitudinally-movable follower against which the spring abuts, an incline on said follower, and a pressure-transmitting member movable longitudinally or in the direction of movement of the follower and having an incline at an angle to the incline on the follower, of a transversely-movable wedge-block interposed between said inclines whereby the longitudinal movement of said pressure-transmitting member or follower will impart an opposite movement to the other member; substantially as described.

7. In a draft-rigging, the combination with the oppositely-located followers, the spring interposed between said followers, and the in-

clines on the outer sides of said followers, of the wedge-blocks coöperating with said inclines, the inwardly-movable cross-plates against which said blocks work, the pressure-transmitting member inclosing said followers, spring and cross plates and inclines on said pressure-transmitting member coöperating

with the wedge-blocks; substantially as described.
